US00D327012S

United States Patent [19]**Gavala, Jr. et al.****[11] Patent Number: Des. 327,012****[45] Date of Patent: ** Jun. 16, 1992****[54] BOTTLE**

[75] Inventors: Michael J. Gavala, Jr., Ortley Beach, N.J.; Larry Kurzweil, Ossining, N.Y.; Joseph G. Shaw, Brigantine; Richard H. Staehle, III, Vineland, both of N.J.

[73] Assignee: Deer Park Spring Water, Inc., Carlstedt, N.J.

[**] Term: 14 Years

[21] Appl. No.: 583,766

[22] Filed: Sep. 14, 1990

[52] U.S. Cl. D9/568; D9/570; D9/573

[58] Field of Search .... D9/403-413, D9/401, 370, 396, 397, 350, 351; 215/1 R, 1 C

UNITED STATES PATENT AND TRADEMARK OFFICE
CERTIFICATE OF CORRECTION

PATENT NO. : Des. 327,012
DATED : June 16, 1992
INVENTOR(S) : Michael J. Gavala, Jr, et al

Page 1 of 5

It is certified that error appears in the above-identified that said Letters Patent is hereby corrected as shown below:

The title page showing the illustrative Figure should be deleted to be substituted with the attached page.

In the drawings sheets 1 and 2, consisting of Figs. 1-5, should be deleted to be replaced with sheets 1-3, consisting of Figs. 1-5, as shown on the attached pages.

Signed and Sealed this
Second Day of August, 1994

Attest:

BRUCE LEHMAN

Attesting Officer

Commissioner of Patents and Trademarks
